UNITED STATES PATENT OFFICE.

JOHN F. SPERBER, OF NEW YORK, N. Y., ASSIGNOR, BY DIRECT AND MESNE ASSIGNMENTS, TO AMERICAN GAS GOVERNOR WORKS, INC., OF NEW YORK, N. Y., A CORPORATION OF NEW YORK.

GAS-REGULATOR.

1,179,571.

Specification of Letters Patent.

Patented Apr. 18, 1916.

Application filed July 25, 1914. Serial No. 853,208.

To all whom it may concern:

Be it known that I, JOHN F. SPERBER, a citizen of the United States of America, residing in the borough of Manhattan, city, 5 county, and State of New York, have invented certain new and useful Improvements in Gas-Regulators, of which the following is a specification.

My invention relates to a regulator or 10 governor for maintaining a uniform and unvarying pressure upon gas at the burners, notwithstanding fluctuations in pressure in the supply pipe, and notwithstanding variations in pressure in the service pipe, due to 15 varying consumption at the burners, or to other causes.

The object of my invention is to provide 20 a gas pressure regulator which shall be extremely sensitive in action and which may be readily adjusted to deliver gas at any desired pressure.

My invention consists in the provision of 25 means for maintaining a uniform pressure in the service pipes notwithstanding fluctuations in pressure in the supply. By my invention also, upon a sudden drop in pressure in the service pipes, due to an increase 30 in consumption, the volume of gas supplied through the meter is increased without any increase in the pressure.

A further object of my invention is to 35 provide an improved construction of regulator wherein the parts may be easily taken apart for the purpose of cleaning the same.

Further objects of the invention will appear 40 as the description proceeds.

A desirable form in which my invention may be embodied is illustrated in the accompanying drawing, wherein,—

Figure 1 is a central vertical section on 45 the line 1—1, Fig. 2. Fig. 2 is a plan view partly in section thereof on the line 2—2 in Fig. 1.

The apparatus illustrated in the accompanying drawing comprises a base A having 50 on the inlet or high pressure side, inlet pipes D, D' leading to the inner or high pressure chamber a. A plurality of inlet pipes is provided to facilitate the connection to the supply pipes. The outlet pipe E leads from the outer or low pressure chamber a'. These chambers are separated by a partition I

carrying the valve seat i, which receives the main inlet valve G.

Above the base A is a sealing chamber 55 which comprises a reservoir B adapted to receive the sealing liquid T, for which purpose mercury is usually employed. This is provided with a cover C, and to prevent the leakage of the sealing liquid during the 60 handling of the device, I prefer to provide the reservoir and cover with shoulders b, c forming a species of tongue-and-groove connection between the two. The said cover is then secured to the reservoir by bolts 65 passing through flanges in each of the parts, as illustrated. Reservoir B has a dome b' formed therein, whereby outer and inner channels t, t' are formed, and these receive the outer and inner floats J, K. A passage 70 b² is provided between the said channels for the purpose of permitting the insertion of the sealing liquid therein. I have illustrated the outer and inner floats as being concentrically arranged, which is my preferred 75 construction, and these are supported upon the stem F of the main valve G, whereon they are held in adjusted position by lock-nuts j, k. A hood U is supported upon this stem and carries the usual weights L, of 80 which any number may be provided, according to the pressure desired. These are inserted through an opening in the cover C, 85 which is closed by a screw-cap R, this being made removable for the purpose of changing the said weights as desired, and preferably being held in place by suitable means such as the pad-lock r, whereby interference with the device is prevented.

To prevent the loss of the mercury in handling the regulator, the usual vent hole S is provided with an inwardly extending tubular sleeve S¹, so that upon inversion of the apparatus the mercury will not flow out of the vent, but will be prevented by the said 95 sleeve.

A passage N is provided between the inner chamber a and the inner float K, and this passage I call the inner passage. By its means the gas pressure of the supply pipe D 100 or D' is communicated beneath the float K, where it performs its function. In case the consumption of gas in the service pipes should cease, the increase in pressure will

cause the float *J* to be lifted, causing the main valve *G* to close or substantially so, and at the same time an auxiliary valve *H'* which is adjustably held in place upon the 5 main valve stem *F* by lock-nuts *h*¹, *h*² will likewise be raised and will substantially close the inner passage, whereby blowing out of the mercury in the sealing chamber will be prevented. A corresponding outer passage *M* leads from the outer chamber *a'* to the outer float *J*. The said passage comprises a tube *M*, part of which may be formed integral with the mercury holder *B*, and which will have its upper end above the 10 normal level of mercury in the said mercury holder, and part of which may be formed as an extension of the said tube and threaded into the base *A*.

An important feature of my invention 20 consists in the provision of means whereby the pressure may be maintained constant in the service pipes, whether or not there is a sudden increase in the supply pipe pressure or a sudden drop in pressure in the service 25 pipes, due to an increase in consumption at the burners. This feature of my invention is accomplished by the provision of means whereby a sudden inflow of gas is prevented from affecting the pressure in the outer float 30 *J*. The said means as illustrated, comprises an auxiliary valve *H* which may be formed, as shown, as a cup-shaped valve which is adapted to nearly close the lower end of the tube *M*. This, as illustrated, is operated by 35 the lowering of the floats upon a sudden drop in pressure, and a desirable manner of accomplishing this result is that illustrated wherein a bar *O*¹ is pivotally mounted at *o* upon a post *O* supported in a base plate *V*. 40 One end of the said bar extends under the valve stem *F*, and the other end extends within a slot *h* in the stem of the auxiliary valve *H*, and is there provided with a reduced bearing *o*¹. Thereby, as the valve 45 stem *F* falls upon a sudden drop of pressure, the main valve *G* opens, and at the same time the auxiliary valve *H* is raised to its working position substantially as shown in Fig. 1, in which position it substantially 50 closes the bottom of the tube *M* and protects it from the flow of the increased volume of gas coming in, and prevents any substantial increase of pressure in the outer float *J*. I prefer to provide means for guiding the said 55 auxiliary valve *H*, and such means as illustrated comprise a stem extension *H*² upon the said auxiliary valve *H* which is received in a short guiding tube *P* that is mounted in the said base plate *V*. A set screw *Q* is 60 threaded in tube *P* and provides an adjustable stop for stem *H*². A lock-nut *Q'* maintains the said screw *Q* in adjusted position.

A second auxiliary valve *H'* is mounted so as to close the inner passage *N* upon a 65 sudden increase in pressure, and as illus-

trated, such valve is supported directly upon the main valve stem *F*, and is capable of being adjusted in position thereon and held in such adjusted position by suitable adjustment of the lock-nuts *h*¹, *h*². Means are likewise provided for adjusting the main valve *G* in position and for holding it in position, comprising the nut *g*.

An important feature of my invention is the provision of the auxiliary valve *H* or some equivalent means for checking the increase in pressure in the outer float *J* upon the increase in flow of gas through the regulator, and by means of this apparatus the pressure of gas is maintained at a substantially uniform point, irrespective of variations in the consumption. In actual practice the invention has been found to maintain substantially unvarying pressure in gas in the service pipe in the presence of a varying demand.

In the operation of my invention the gas enters the inlet or high pressure chamber *a* through either inlet indicated in the drawings as *D* or *D'*, and passes upward through the passage *N* into the inner float *K*, and at the same time through the main valve *G*, and fills the service pipes ready for consumption. The surplus gas then passes upward through the auxiliary valve *H* into the outside float. This causes both floats to rise and move the main valve toward the closing position, and with it the auxiliary valve *H'* which is maintained rigidly on the main valve spindle. By this action the balance bar *O'* is released and the auxiliary valve *H* drops by its weight into its guiding socket *P* where it rests upon the adjustable screw *Q* and the entrance to the outer passage *M* is fully open and both the floats are available to regulate the pressure. During the operation of the device the lower edge of the inner and outer floats will be at all times immersed in the mercury in the sealing chambers *t*, *t'*. If the pressure of the incoming gas upon the floats exceeds the weight of the floats together with the adjusting weights *L*, both floats will be raised sufficiently to restrict the opening in the main valve seat so as to allow only a proper flow of gas therethrough. The number and sizes of the adjusting weights *L* may be varied as required. The gas from the outer gas chamber *a'* will pass up through the outer tube *M* into the outer float *J*, and act upon the said float, thereby controlling the pressure unvaryingly at all times, with economy. If the system is working under a normal demand and the inlet valve is adjusted to meet this demand and there should follow a sudden and large increase in consumption of gas, requiring a largely increased volume of supply, this will cause a sudden release of pressure in the service pipes and in the regulator, which will cause the floats to drop,

opening the inlet valve G and permitting a much larger amount of gas to enter. The normal effect of this sudden increase, if the apparatus were not provided with the auxiliary valve H, would be to cause an increase in pressure in both the inner and outer floats, which would tend to raise the 5 said floats and partially close the main valve, which would produce a fluctuating 10 pressure and irregular operation at the burners. By the provision, however, of the auxiliary valve H, I cause the tube leading to the outer float to be partially closed when the main valve G opens, and thereby 15 the inrush of gas caused by the said opening of the main valve will be deflected away from the bottom of the outer tube M, and will not affect the pressure in the outer 20 float J, which will be less than that in the inner float K. This will cause the floats to be maintained at a lower level and will consequently increase the supply of gas entering into the main valve. At the same 25 time the weights L will maintain the uniform and desired pressure in the service pipes. It will therefore be seen that broadly speaking, my invention contemplates the provision of means whereby at desired times one or the other of the floats will be relieved of the pressure of gas, so that while 30 the pressure upon the gas in the service pipes is maintained at a uniform and desired amount, the volume of gas entering through the inlet will be much larger, owing to the fact that but one of the floats receives the pressure of the incoming gas. 35 By supply pipes I refer to the pipes on the supply side of the regulator, and by service pipes I refer to the pipes on the 40 consumption side of the regulator. The inner float is that on the supply side, and accordingly I have termed the corresponding chamber in the regulator as the inner chamber, and the passage connecting the two 45 as the inner passage. The corresponding float, chamber and passage on the consumption side, I have termed the outer members. 50 A valuable feature of my invention is that whenever gas is used under forced draft (air pressure), the air in the air supply pipes which frequently backs into the gas supply pipes will cause the floats to rise and close the main valve tight, thus preventing a break of the gas meter and an 55 explosion which consequently would follow. Another important feature of my invention and a valuable safeguard is that an impulsive extremely high pressure on the inlet side of the regulator will immediately close 60 both the main valve and the auxiliary valve H', thus preventing the mercury seal from being forced out of the channels of the float holder B, thereby unsealing the regulator. 65 Although I have illustrated a plurality of inlet passages D, D', these are provided for the purpose of convenience and to enable the mechanic to easily make connections in the most convenient manner, and it is not desired to employ more than one 70 of the said passages, and the other one will be sealed up.

I have illustrated in the accompanying drawings, and have described in the foregoing description, the preferred manner of 75 constructing my gas regulator, which is the best now known to me, but it is within the skill of the gas engineer to modify the same and employ equivalent constructions without departing from the real scope of my invention within the limits of the appended 80 claims.

What I claim is:

1. A fluid pressure regulator comprising an inlet pipe, a partition therein dividing the same into high and low pressure chambers, said partition having an inlet port, a main valve adapted to close said port, a sealing chamber communicating with said high pressure chamber, and a sealing chamber 85 communicating with said low pressure chamber, and a valve adapted to restrict said last named communication adapted to operate oppositely to said main valve.
2. In a gas regulator, a gas supply pipe, a main valve therein, a sealing chamber, floats therein connected to said valve; passages connecting said floats and the outlet and inlet sides of the supply pipe respectively, and an auxiliary valve adapted to restrict the 90 passage to the outlet float, and means for closing same as the main valve opens.
3. In a gas regulator, a gas supply pipe, a main valve therein, a sealing chamber, floats therein connected to said valve; passages connecting said floats and the outlet and inlet sides of the supply pipe respectively, and an auxiliary valve adapted to restrict the 95 passage to the outlet float operated by the main valve and adapted to restrict said passage as the main valve opens.
4. A fluid pressure regulator having a high pressure chamber communicating with the supply pipe, and a low pressure chamber communicating with the service pipe, a sealing chamber containing passages connecting one float to the high pressure chamber and the other float to the low pressure chamber; a main valve controlling a passage between 100 said chambers and operated by said floats, and an auxiliary valve controlling the passage to the outer float, and means whereby said auxiliary valve is adapted to restrict 105 said passage as the main valve opens.
5. A fluid pressure regulator having a high pressure chamber communicating with the supply pipe, and a low pressure chamber communicating with the service pipe, a sealing chamber containing outer and inner 110 floats, passages connecting the inner float to 115

- the high pressure chamber and the outer float to the low pressure chamber; a main valve controlling a passage between said chambers and operated by said floats, and
- 5 an auxiliary valve controlling the passage to the outer float, and a second auxiliary valve adapted to restrict the passage to the inner float as the main valve closes.
6. A gas regulator provided with high and low pressure chambers communicating respectively with the supply and service pipes, a main valve controlling an inlet passage between said chambers, a sealing chamber, inner and outer floats therein, and passages connecting said high and low pressure chambers with said inner and outer floats respectively; means whereby upon a sudden release in pressure in the low pressure chamber, the main valve is opened and the passage connecting the outer float to the low pressure chamber is restricted.
7. A gas regulator provided with high and low pressure chambers communicating respectively with the supply and service pipes, a main valve controlling an inlet passage between said chambers, a sealing chamber, inner and outer floats therein, and passages connecting said high and low pressure chambers with said inner and outer floats respectively; a device for restricting the passage from the low pressure chamber to the outer float adapted for operation upon an opening of the main valve, whereby upon a sudden drop in pressure in the low pressure side, the main valve is opened to increase the supply, and means whereby the outer float is shielded from the increased pressure due to such increased supply and the volume is increased while the pressure is maintained.
8. A gas regulator, comprising inner and outer chambers, a main valve separating said chambers, a sealing chamber having inner and outer floats, means whereby said main valve is controlled by the movement of said floats, inner and outer passages between said inner and outer chambers and the corresponding floats respectively, an auxiliary valve on said valve stem adapted to restrict the inner passage as the pressure in the inner chamber rises, and an auxiliary valve adapted to restrict the outer passage as the pressure in the outer chamber drops.
9. In a gas regulator, a main gas inlet valve, a float having separate gas receiving receptacles controlling the same, and passages leading to each receptacle, a device adapted to operate in opposition to the main valve, said device adapted to restrict one of said passages as the main valve opens, whereby upon a drop in pressure in the service side of the regulator and a consequent opening of the main valve and increase in the volume of gas admitted, a passage leading to one of the floats will be restricted and a portion of the float will be shielded from an increase in pressure from the increased flow, whereby the controlling effect of the float will be diminished.
10. A gas regulator, having inner and outer chambers, a sealing chamber, inner and outer floats therein, inner and outer passages connecting said respective inner and outer chambers and floats, a main valve controlling an inlet passage between said inner and outer chambers, a stem therefor supporting said floats, a sealing liquid for said floats, an auxiliary valve adapted to restrict the outer passage as the floats drop, and an auxiliary valve adapted to restrict the inner passage as the floats rise.
11. A gas regulator having inner and outer chambers, a sealing chamber containing inner and outer floats therein, inner and outer passages connecting said respective inner and outer chambers and floats, a main valve controlling an inlet passage between said inner and outer chambers, a stem therefor supporting said floats, a sealing liquid for said floats, an auxiliary valve adapted to restrict the outer passage as the floats drop, and means for operating said valve comprising a pivoted bar interposed between said main valve and said auxiliary valve, and adapted to move said valve toward its closing position as the main valve opens.
12. A gas regulator having inner and outer chambers, a sealing chamber, inner and outer floats therein, a tube connecting said outer float to said outer chamber, a connection between the inner chamber and inner float, a main valve controlling an inlet passage between said inner and outer chambers, a stem therefor supporting said floats, a sealing liquid for said floats, an auxiliary valve of cup shape underlying said tube and adapted to move toward the same and tending to close the entrance to said tube as the floats rise, and means for operating said valve comprising a bar pivotally mounted in said regulator, one end of which is adjacent to the main valve or its parts, and the other end is adjacent to said auxiliary valve.
13. A gas regulator having inner and outer chambers, a sealing chamber, inner and outer floats therein, inner and outer passages connecting said respective inner and outer chambers and floats, a main valve separating said chambers, an auxiliary valve adapted to restrict said outer passage, and a removable plate supporting said valve, upon the removal of which said valve and its connected parts may be removed and the main valve may be removed.
14. A fluid pressure regulator comprising high and low pressure chambers, a main valve controlling a port leading from one to the other of said chambers, a sealing chamber communicating with the high pressure chamber, and a sealing chamber communi-

cating with the low pressure chamber, and a valve adapted to restrict said last named communication, said valve adapted to be operated in conjunction with, but in opposition to, the main valve, whereby said valve is closed as the main valve opens.

5 In witness whereof, I have hereunto

signed my name in the presence of two subscribing witnesses.
